SLIDABLE PANE MOUNTING FOR WINDOWS

Farr Nutter, Elkins, W. Va.

Application September 13, 1948, Serial No. 48,987

8 Claims. (Cl. 20—52)

1

This invention relates to an improvement in windows and pertains particularly to window construction in which a pane of glass or the equivalent is slidable and is frictionally held so as to be adjustable to any predetermined position.

In my application Serial No. 739,139, filed April 3, 1947, I have disclosed a window with slidable panes, in which a pane of glass or the equivalent slides vertically in grooves provided in the opposed sides of the window frame. In the construction as shown in that application, the front side of the groove in the side framework is adjustable with respect to its distance from the back side of the groove, whereby the slidable pane is frictionally engaged by the sides of the grooves to be held in any predetermined position.

The window construction herein disclosed is an improvement upon the construction shown in the said prior application. In the present case the slidable glass pane is provided with a metallic strip which extends along the edges of the pane and is bent around over a portion of both faces of the pane and then backwardly at an acute angle to form wing portions which may press against the sides of the grooves which receive the slidable pane for the purpose of frictional engagement which is sufficient to hold the pane in any predetermined position.

An additional feature of the present construction is that the metallic strip not only enables the slidable pane to be adjustably positioned in the frame, but in the closed position this strip engages cross bar members which extend between the side portions of the window frame, to form a seal against the passage of air through the window and make it weather-tight.

Other features and advantages of my invention will be obvious from the following description and accompanying drawing, in which:

Fig. 1 is an elevational view of the face of a window of the present construction;

Fig. 2 is a sectional view taken on the line 2—2 of Fig. 1 looking in the direction of the arrows;

Fig. 3 is a sectional view taken on the line 3—3 of Fig. 1 looking in the direction of the arrows;

Fig. 4 is a fragmentary view of a corner of a slidable pane showing a detail of the metallic strip;

Fig. 5 is a sectional view taken on the line 5—5 of Fig. 4 showing the cross sectional contour of the metallic strip; and

Fig. 6 is an enlarged sectional view taken on the line 6—6 of Fig. 1.

Referring in detail to the several figures of the drawing, like reference characters identify like structural parts.

Fig. 1 illustrates a preferred embodiment of my invention in which, for the sake of illustration, there is shown a window provided with four panes of glass, of which the two lower ones are

2

slidable vertically, while the upper ones are fixed in place. The framework comprises the vertical side rail members 6 and 7, and an intermediate vertical rail member, or muntin 11. Cross bar members 8, 9, and 10 extend horizontally between the vertical rail members 6, 7, and 11. The fixed glass panes 13 are inserted in the two upper openings formed by the vertical members 6, 7 and 11 together with the horizontal members 9 and 10 in any suitable manner. The means used for this purpose forms no part of the present invention.

The slidable panes are indicated by the reference numeral 12. Hand grip lifting elements 14 are shown on each of the slidable panes 12. For the purpose of slidably supporting the right hand pane 12, as shown in Fig. 1, the vertical elements 7 and 11 may be provided with opposed grooves to receive the pane 12. These grooves will extend upwardly as far as it will be desired to permit the slidable pane to be moved, which may be the entire height of the framework of the window. Obviously, these grooves will be placed in a plane parallel to, but spaced from the plane of the upper panes 13. The vertically extending groove provided in the rail member 7 is shown in Fig. 3 as having side portions 16, and 17, while in the opposed vertical rail member 11, the groove is provided with side portions 18, and 19. In the construction shown, the side 17 of the groove provided in the member 7 and the side 19 of the groove provided in the member 11 are actually a portion of the inner faces of the mounting strips 7a, and 11a, respectively, attached to the members 7 and 11 by means of screws 15. This type of construction is described and claimed in my prior application Serial No. 739,139, and forms no part of this invention, and it will be obvious that the groove may be cut entirely within the members 7, and 11.

The cross bar 8 is provided with a groove which has sides 20 and 21 (as shown in Fig. 3). The surface 20 is substantially coplanar with the surfaces 16 and 18, and the surface 21 is substantially coplanar with the surfaces 17, and 19, in order that the lower edge of the slidable pane 12 may be slid into a position adjacent to the surfaces 20 and 21 when closed. The cross bar member 9 is mortised in a vertical direction to permit the pane 12 to slide therethrough. The mortised interior portion of the cross bar 9 will therefore be provided with surfaces 22 and 23 adjacent to the upper edge of the pane 12 when closed. The surface 22 is formed substantially coplanar with the surfaces 16, and 18, while the surface 23 is formed substantially coplanar with surfaces 17, and 19.

The framework which surrounds the left hand slidable pane 12, in which the opposed grooved rails are represented by the vertical members 9,

and 11 will be similarly constructed in a manner which will be obvious to one skilled in the art. It will be understood that a window built according to the teachings of my invention will not be limited to having two slidable panes placed side by side. Obviously any number of slidable panes could be provided in any desired arrangement of upper and lower panes, and furthermore with suitable modifications of construction which will be obvious, these panes may be arranged for slidable movement in a horizontal as well as vertical direction.

The means which provides for a weather-tight fit for the slidable panes 12 as well as a frictional engagement between the pane and the grooved frame members comprises a metallic strip 24 which extends over the four edges of the pane 12. This may be a single flat strip which is first bent around the corners and whose abutting end portions may then be joined, such as by soldering. The strip is then bent along its length over a portion of each face of the pane 12, as indicated by the reference numerals 25, and 26 in Fig. 5. In order to provide a resilient frictional engagement with the framework of the window the metal strip is also provided with wing portions 27, and 28 which form acute angles with the portions 26, and 25, respectively. The extremities 27a and 28a of the wing portions are bent toward the adjacent face of the pane 12 while intermediate surfaces 27b and 28b provide the actual engaging portions of the wing members 27 and 28 respectively. In the formation of the strip 24 it is desirable to cut away portions of the elements 25, 26, 27, and 28 at the corners of the pane, as shown in Fig. 4, in order to avoid double thicknesses of the metal and to provide substantially smooth surfaces.

In operation, when the slidable pane is closed, as exemplified by the left hand pane in Fig. 1, the intermediate surface 27b will be in resilient frictional engagement with the back side of the grooves provided in the vertical members 6, and 11, as well as the back side of the adjacent coplanar surfaces provided in the cross bar members 3, and 9, while the intermediate surface 28b will be in resilient frictional engagement with corresponding surfaces in front of the pane. The result will be a weather-tight fit for the pane 12 which will not allow the passage of air through the window.

When the pane is opened, as exemplified by the right hand pane 12 in Fig. 1, it may be lifted by means of the hand grip 14 which causes the pane to slide upwardly through the mortised opening provided in the cross bar member 9. The surfaces 27b and 28b which were previously in engagement with adjacent surfaces provided in cross bar members 3 and 9 will become disengaged, but the surfaces 27b and 28b adjacent the sides of the grooves in the vertical rails 7 and 11 will remain in frictional engagement at all times to hold the pane 12 in any position to which it may be adjusted. When the pane is pushed downwardly to close it, the surfaces 27b and 28b, 65 will again engage the surfaces 22, and 23 in the cross bar 9, and surfaces 20 and 21 in cross bar 6, to assure weather-tightness of the window.

The lifting elements 14 are preferably metal members having a lip 14a projecting beneath the lower edge of the pane and a main portion extending from the lip upwardly alongside of the pane to a point above the spring strip wing portions 27a, 28a, and thence turned laterally away from the pane to provide a finger engaging hook 75 jacent to an edge of the pane when it is in a closed

portion 14b. This lifting element construction is shown in side sectional view in Fig. 6.

I claim:

1. A window comprising a slidable pane and a fixed frame having a pair of opposed grooved rails for supporting the slidable pane, members of sheet metal extending along the edges of the pane which slide in the grooves, said metallic members being movable with said pane and slidable with respect to the grooves and being bent to extend over a portion of one face of said pane, said metallic members having a wing portion bent to form an acute angle with the portion extending over the face of the pane, that edge portion of the wing portions of said metal members distant from said acute angle extending toward the plane of the pane so that an intermediate surface of the wing portion frictionally and resiliently engages with the side of said grooves, and means to fasten said metallic members to the pane to be movable therewith.

2. A window comprising a slidable pane and a fixed frame having a pair of opposed grooved rails for supporting the slidable pane, members of sheet metal extending along the edges of the pane which slide in the grooves, said metallic members being movable with said pane and slidable with respect to the grooves and being bent to extend over a portion of both faces of said pane, said metallic members having wing portions bent to form an acute angle with the portions extending over the faces of the pane, that edge portion of the wing portions of said metal members distant from said acute angle extending toward the plane of the pane so that an intermediate surface of each wing portion frictionally and resiliently engages with a side of said grooves, and means to fasten said metallic members to the pane to be movable therewith.

3. A weather-tight window comprising a slidable pane, and a fixed framework for supporting the slidable pane, two opposed sides of which are provided with grooves to receive the pane for slidable movement, said framework also having a pair of spaced cross bars extending between the opposed sides, a portion of each of the cross bars having a surface which is substantially coplanar with one side of said grooves and adjacent to an edge of the pane when it is in its closed position, a strip of sheet metal extending about the four edges of the pane, said metallic strip being bent along substantially its entire length over a portion of one face of said pane, and having a co-extensive wing portion bent to form an acute angle with the portion extending over the face of the pane, that edge portion of the wing portions of said metal members distant from said acute angle extending toward the plane of the pane so that an intermediate surface of the wing portion yieldably and frictionally engages with the side of said grooves in all positions of the pane, and engages with said surfaces of the cross bars when the pane is in its closed position, and means to fasten the metallic strip to the pane.

4. A weather-tight window comprising a slidable pane, and a fixed framework for supporting the slidable pane, two opposed sides of which are provided with grooves to receive the pane for slidable movement, said framework also having a pair of spaced cross bars extending between the opposed sides, a portion of each of the cross bars having surfaces which are substantially coplanar with the sides of said grooves, the surfaces of each of the cross bars being substantially adjacent to an edge of the pane when it is in a closed

position, a strip of sheet metal extending about the four edges of the pane, said metallic strip being bent to extend over a portion of both faces of said pane, said metallic strip having co-extensive wing portions bent to form an acute angle with the portions extending over the faces of the pane, that edge portion of the wing portions of said metal members distant from said acute angle extending toward the plane of the pane so that an intermediate surface of each wing portion frictionally and resiliently engages with the sides of said grooves in all positions of the pane, and engages with said surfaces of the cross bars when the pane is in its closed position.

5. A window comprising a slidable pane, a fixed frame having a pair of opposed grooved rails for supporting the slidable pane, members of sheet metal extending along the edges of the pane which slide in the grooves, said metallic members being bent to extend over a portion of one face of said pane, said metallic members having a wing portion bent to form an acute angle with the portion extending over the face of the pane, that edge portion of the wing portions of said metal members distant from said acute angle extending toward the plane of the pane so that an intermediate surface of the wing portion frictionally and resiliently engages with the side of said grooves, and means to fasten said metallic members to the pane, a window pane fastening element comprising a portion of the frame mounted to exert pressure on said wing portion at right angles to the face of the pane, and adjusting means cooperating with said fastening means and said frame for adjustably regulating the tension of said fastening means with respect to said wing portion and to the face of the pane whereby the pane may be held in any predetermined vertical position.

6. A window comprising a slidable pane, a fixed frame having a pair of opposed grooved rails for supporting the slidable pane, members of sheet metal extending along the edges of the pane which slide in the grooves, said metallic members being bent to extend over a portion of both faces of said pane, said metallic members having wing portions bent to form an acute angle with the portions extending over the faces of the pane, that edge portion of the wing portions of said metal members distant from said acute angle extending toward the plane of the pane so that an intermediate surface of each wing portion frictionally and resiliently engages with a side of said grooves, and means to fasten said metallic members to the pane, a window pane fastening element comprising a portion of the frame mounted to exert pressure on said wing portion at right angles to the face of the pane, and adjusting means cooperating with said fastening means and said frame for adjustably regulating the tension of said fastening means with respect to said wing portion and to the face of the pane whereby the pane may be held in any predetermined vertical position.

7. A weather-tight window comprising a slid- 65 able pane, a fixed framework for supporting the slide- able pane, two opposed sides of which are pro- vided with grooves to receive the pane for slide- able movement, said framework also having a pair of spaced cross bars extending between the op- posed sides, a portion of each of the cross bars having a surface which is substantially coplanar with one side of said grooves and adjacent to an edge of the pane when it is in its closed po- sition, a strip of sheet metal extending about 75

the four edges of the pane, said metallic strip being bent along substantially its entire length over a portion of one face of said pane, and having a co-extensive wing portion bent to form an acute angle with the portion extending over the face of the pane, that edge portion of the wing portions of said metal members distant from said acute angle extending toward the plane of the pane so that an intermediate surface of the wing portion resiliently and frictionally engages with the side of said grooves in all positions of the pane, and engages with said surfaces of the cross bars when the pane is in its closed position, and means to fasten the metallic strip to the pane, a window pane fastening element comprising a portion of the framework mounted to exert pressure on said wing portion at right angles to the face of the pane, and adjusting means co-operating with said fastening means and said framework for adjustably regulating the tension of said fastening means with respect to said wing portion and to the face of the pane whereby the pane may be held in any predetermined vertical position.

8. A weather-tight window comprising a slide- able pane, a fixed framework for supporting the slide- able pane, two opposed sides of which are pro- vided with grooves to receive the pane for slide- able movement, said framework also having a pair of spaced cross bars extending between the op- posed sides, a portion of each of the cross bars having surfaces which are substantially coplanar with the sides of said grooves, the surfaces of each of the cross bars being substantially adja- 30 cent to an edge of the pane when it is in a closed position, a strip of sheet metal extending about the four edges of the pane, said metallic strip being bent to extend over a portion of both faces of said pane, said metallic strip having co-ex- 35 tensive wing portions bent to form an acute angle with the portions extending over the faces of the pane, that edge portion of the wing portions of said metal members distant from said acute angle extending toward the plane of the pane so that an intermediate surface of each wing portion frictionally and resiliently engages with the sides of said grooves in all positions of the pane, and engages with said surfaces of the cross bars when the pane is in its closed position, a window pane fastening element comprising a portion of the framework mounted to exert pres- 40 sure on said wing portion at right angles to the face of the pane, and adjusting means co-operating with said fastening means and said framework for adjustably regulating the tension of said fastening means with respect to said wing portion and to the face of the pane whereby the pane may be held in any predetermined vertical position.
